UNITED STATES PATENT OFFICE.

ANTHONY AQUILA, OF ISELIN, NEW JERSEY.

PRICE-CARD HOLDER.

Application filed November 12, 1926. Serial No. 147,929.

This invention relates to price card holders and more particularly refers to devices for displaying price cards adapted to be attached to the edge of a shelf for indicating the price of articles arranged upon said shelf.

The primary object of this invention is to provide a price card holder of a novel and improved construction, adapted to be readily attached to or detached from shelves of different thicknesses.

Another object of the invention is to provide a price card holder having adjustable means for clamping it onto the edge of a shelf, said means being readily adjustable to correspond to the thickness of the shelf on which the device is to be used.

A further object is to provide a price card holder so constructed that price cards may be readily inserted into and removed therefrom without the necessity of bending or otherwise distorting the same.

A still further object is to provide a price card holder having adjustable attaching means permitting the same to be clamped onto a shelf or else permitting the same to be attached onto the face of said shelf, or else onto the face of a case or counter.

A still further object is to provide a device of the character specified provided with adjustable clamping means also adapted for use as a support or easel for the device, permitting the same to be placed upon a counter at the proper angle for effectively displaying the indications carried by said device.

Still another object is to provide a price card holder combining a simple and inexpensive construction with an effective display of the indications printed upon the cards inserted therein, each figure showing through an opening providing a frame therefor, this constituting an ornamental feature which noticeably improves the appearance of the device.

Other objects and advantages of the present invention will more fully appear as the description proceeds and will be set forth and claimed in the appended claims.

A preferred embodiment of my invention is illustrated in the accompanying drawings, in which:

Fig. 1 is a front view in elevation of my improved price card holder;

Fig. 2 is a plan view of the same;

Fig. 3 is a side view in elevation of the same;

Fig. 4 is a side sectional view in elevation through line 4—4 of Fig. 1, showing the device clamped onto the edge of a shelf;

Fig. 5 is a plan sectional view in elevation through line 5—5 of Fig. 1;

Fig. 6 is a rear view in elevation of the same;

Fig. 7 is a side view in elevation of the device showing the same applied onto a shelf, the thickness of which exceeds the clamping capacity of the device;

Fig. 8 is a side view in elevation of the device illustrating the same placed upon a counter in an inclined position;

Fig. 9 is a front view in elevation of the set of cards used in the arrangement of Fig. 1; and

Fig. 10 illustrates an alternative type of sectional card which may be used to provide indications supplementary to the figures indicating the price proper.

My device comprises, essentially, a body or card holding portion, and means carried thereby for attaching or supporting the device in position, these means being preferably of an adjustable nature. The card holding portion comprises a front plate 11 and a rear plate 12, formed from a single piece of sheet metal, bent to form a loop at the lower end as shown at 13, leaving an open slot 14 at the upper end through which a price card or a plurality of price cards 15 may be inserted. Said card or cards may bear any suitable indication such as for instance, price indications which are positioned so as to register and show through openings such as 16, 17, 18, 19, provided in the front plate.

Said openings may have any desired or suitable outline and practically constitute frames through which the various figures or other indications may show through. In this manner said figures or indications may be effectively displayed, due to the contrast between the color of the plate and the color of the underlying card, and this provides an ornamental feature of great practical value.

The two side edges of the front plate, or portions thereof, are bent rearwardly and then inwardly, forming two flanges 20, 21, retaining the two plates in their proper relative position.

In order to secure the device onto the edge of a shelf as shown in Fig. 4, the same may be provided with two spaced rearwardly projecting clamping flanges 22, 23, which may be permanently attached to the rear plate when the device is intended for use in connection with shelves of a predetermined and uniform thickness.

Said clamping flanges are to a certain extent resilient and may also be bent inwardly or outwardly to suit small variations in the thickness of the shelf. However, in order to produce a device adapted for universal use, I prefer to make one of the said clamping flanges adjustable so that the distance between said two flanges may be increased or decreased at will.

Accordingly, I make the upper clamping plate 22 stationary by forming it directly with the rear plate, rearwardly bending the upper part of said plate at 24. Said clamping flange is preferably formed with a longitudinal bead or depression 25 embossed therefrom so as to project inwardly providing a better clamping contact with the surface of the shelf.

The lower clamping flange 23 is made adjustable to and from the stationary flange and consists of a piece of resilient sheet metal bent at right angle to form a horizontal portion constituting the clamping flange proper 23, and a vertical holding portion 26 having two side projecting lugs 27, 28, inserted between the rear surface of the rear plate 12, and the inner surface of side flanges 20, 21.

To this end, said side flanges 20, 21, are spaced from the rear plate to provide a slotted passage of sufficient width to accommodate the thickness of part 26.

Said part 26 is retained in position by the spring action of the rear plate against the inner surface of flanges 20, 21. The tendency of rear plate 12 is naturally to spread outwardly towards flanges 20, 21, and therefore due to this tendency, part 26 will be securely held in position, by said rear plate.

In order to change the position of the lower clamping flange, the rear plate is pressed inwardly, that is, away from flanges 20, 21, before inserting the price cards in position within the card holding chamber 29. This releases the side lugs 27, 28 on part 26 and permits free movement of said lower clamping flange to a different position. The rear plate is then released, and the lower clamping flange is once more clamped in position, ready for use.

In order to improve the resiliency of the rear plate, I prefer to extend the loop 13 somewhat to the rear as shown at 30, so as to increase the radius thereof, and thereby improve its spring action.

After adjusting the position of the lower clamping flange, the cards may be placed in position by inserting them through upper

slot 24 and forcing them downwardly through chamber 29 until they rest upon the lower end of said chamber, that is, upon loop portion 13.

By thus inserting the cards in position the clearance space between the front and the rear plate becomes filled so that it is no longer possible to press the rear plate against the front plate in order to release the lower clamping flange for adjustment purposes; therefore, the insertion of the cards acts to a certain extent in assisting the clamping action of the rear plate by tending to force it outwardly; or at least by preventing its possibility of inward displacement.

The card or cards may be easily removed by pressing against them with the thumb through the openings provided in the front plate, and causing the cards to slide out at the upper end through slot 14.

However, it is possible in this manner to soil or deface the cards, and therefore, I prefer to cut notches such as 30, 31, 32 through the lower part of the rear plate, exposing the lower edge 33 of the card or cards. In this manner it becomes possible to engage the edge of the card or cards with the thumb nail and to force the card or cards upwardly until they project sufficiently out of slot 14, to permit of their being pulled out from the other end.

The lower clamping flange is also preferably provided with an inwardly directed longitudinal bead or depression 34 to improve the clamping contact against the lower surface of the shelf.

In some cases, it is not possible to clamp the device in position in the manner illustrated in Fig. 4 due to excessive thickness of the shelf, or due to the fact that the device must be placed on a case or drawer having an unbroken front surface preventing the lower clamping flange from projecting inwardly therethrough.

In order to render the device adapted for use in such instances, I provide the holding part 26 of the lower clamping flange with fine rearwardly projecting points 35, 36, adapted to be forced through the shelf or case onto which the device is placed. By virtue of this arrangement the device may be supported in position in the manner illustrated in Fig. 7, where the lower surface of the lower clamping flange 23 abuts against the upper surface of the shelf or case and the rear surface of the card holder proper abuts against the front surface of said shelf or case, points 35, 36 having been forced through said front surface in the manner indicated.

The device is also adapted for use on a counter, using the lower clamping flange as a rear support therefor. In this case, said lower clamping flange is moved all the way towards the lower end of the card holder.

proper, and the device is then placed on the counter by resting the lower edge of the ticket holder proper and the rear edge of the adjustable clamping flange upon said counter.

In this manner, the front part of the device remains somewhat inclined to the rear at a proper angle for the indications carried thereby to be effectively displayed.

10 The openings through the front plate may be set in any desired arrangement to correspond with the printing on the card or cards used. In order to provide a system having great flexibility, instead of using a single price card, I prefer to form various combinations by using unitary cards, the size of said cards being such that they will fit chamber 29 in the holder when arranged in the proper combination.

15 For instance, in the arrangement illustrated, where the front plate is provided with two main adjoining openings 16, 17, and two superimposed smaller openings 18, 19, at one end, I use two main adjoining cards 37, 38, each one carrying one of the numbers from 0 to 9 positioned so as to show centrally of openings 16, 17, when the two cards are placed adjoining one another, towards the left of the device; furthermore, 20 I use a third card 39 bearing two superimposed indications, one such as ¢ or \$ or Per or For or one of the numerals from 01 to 99 to indicate ¢, etc., positioned so that they will show through the upper opening 18, 25 and lower indications such as Lb., Doz., Two, etc., adapted to register with the lower opening 19; the three cards together arranged so as to abut edgewise against one another as shown in Fig. 9 will just fit the 30 space within chamber 29 and the various indications will show through the front openings as shown in Fig. 1.

In order to further increase the flexibility of the system instead of using a single narrow card 39, for the two fractional or smaller indications, I prefer to use two separate cards such as 40, 41, having the same width as card 39, but shorter, so that their combined length or height will correspond to that of card 39. Each one of these two smaller cards will bear a single indication, so that all possible combinations may be obtained by using a relatively limited number of unitary cards.

35 Said cards however, are preferably printed on both sides in order to increase their usefulness and in order to further decrease the total number of cards needed in order to form all the desired combinations.

40 From the foregoing it is seen that I provide a device of a relatively simple construction, adapted to be used for a number of purposes and providing an attractive and effective means for displaying prices and 45 other indications.

While the drawings represent the preferred embodiment of my invention, it is obvious that minor changes may be introduced in the construction of the device without departing from the inventive idea; therefore, 70 the drawings are to be considered as being intended for illustrative purposes only and not in a limiting sense. Accordingly, I reserve myself the right to carry my invention into practice in any way or manner which 75 may enter fairly into the scope of the appended claims.

I claim:

1. In a card holder of the character specified, a card holding body formed from a 80 piece of sheet metal bent to form a backing member and a front member spaced therefrom, said two members tending to move away from each other and forming an open end card receiving chamber, one of said members having portions of its edges transversal to said open end bent in a front to rear direction and then inwardly to retain the other member in position, and a supporting member frictionally held between 85 said inwardly bent edge portions and the member retained thereby, due to the outward pressure exerted by said retained member. 90

2. In a card holder of the character specified, a card holding body formed from a 95 piece of sheet metal bent to form a backing member and a front member spaced therefrom, said two members tending to move away from each other and forming an open end card receiving chamber, one of said members having portions of its edges transversal to said open end bent in a front to rear direction and then inwardly to retain the other member in position, said front member being provided with openings 100 through which indications carried by cards inserted within said chamber may be displayed, and an adjustable supporting member frictionally held between said inwardly bent edge portions and the member retained thereby, due to the outward pressure exerted by said retained member. 105

3. In a card holder of the character specified, a card holding body formed from a piece of sheet metal bent to form a backing 115 member and a front member spaced therefrom, said two members tending to move away from each other and forming an open end card receiving chamber, said front member being provided with openings through 120 which indications carried by cards inserted within said chamber may be displayed and having portions of its edges transversal to said open end, bent rearwardly and then inwardly to form retaining flanges, and a supporting member frictionally held between 125 said flanges and said backing member, due to the outward pressure exerted by said backing member.

4. In a card holder of the character speci- 130

fied, the combination of a card holding body formed from a piece of sheet metal bent to form a backing member and a front member spaced therefrom, said two members tending to move away from each other and forming an open end card receiving chamber, one of said members having portions of its edges transversal to said open end bent in a front to rear direction and then inwardly to retain the other member in position, and two clamping members therefor, rearwardly projecting from said backing member, one of said clamping members being frictionally held between said inwardly bent edge portions and the member retained thereby, due to the outward pressure exerted by said retained member.

5. In a card holder of the character specified, a card holding body formed from a piece of sheet metal bent to form a backing member and a front member spaced therefrom, the two forming an open end card receiving chamber, one of said members having portions of its edges transversal to said open end bent in a front to rear direction and then inwardly to form retaining flanges, said front member being provided with openings through which indications carried by cards inserted within said chamber may 20 be displayed, a stationary clamping member rearwardly extending from said backing

member, and an adjustable clamping member inserted between said flanges and the rear surface of said backing member, frictionally held in position by the spring action of said backing member against said flanges. 35

6. In a card holder of the character specified, a card holding body formed from a piece of sheet metal bent to form a backing member and a front member spaced therefrom, the two forming an open end card receiving chamber, one of said members having portions of its edges transversal to said open end bent in a front to rear direction 40 and then inwardly to form retaining flanges, said front member being provided with openings through which indications carried by cards inserted within said chamber may 45 be displayed, a stationary clamping member rearwardly extending from said backing member, an adjustable clamping member inserted between said flanges and the rear surface of said backing member, frictionally held in position by the spring action of said 50 backing member against said flanges, and notches cut through the edge of said backing member at the end of the chamber opposite said open end to permit said cards being forced out through said open end. 55

ANTHONY AQUILA.
